CLAIM

The ornamental design for a laptop stand, as shown and described.

DESCRIPTION

FIG. 1 is a rear, left and top perspective view of a laptop stand, showing my design.

FIG. 2 is a front, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines shown in the drawings are included for the purpose of illustrating portions of the laptop stand that form no part of the claimed design.
